UNITED STATES PATENT OFFICE

HARRY HANOVER, OF PHILADELPHIA, PENNSYLVANIA

PERMANENT-HAIR-WAVING APPARATUS

Application filed April 11, 1928. Serial No. 269,046.

My invention relates to improvements in making permanent waves in the hair of the human head.

Hitherto the making of permanent waves in the hair has been attended by numerous disadvantages. Among these may be mentioned the discomfort to the patron due to the intense heat employed which requires the operator to continually use an air cooler or blower upon the head, it oftentimes happening that due to inattention of the operator the patron is subjected to extreme discomfort; scalp burns of serious nature are frequently caused by heated metal parts coming into contact with the scalp due to the employment of unprotected metal parts in the waving or curling units; the waving devices now employed consist of a number of parts which, after the hair has been prepared, are successively joined in a number of steps which requires considerable time on the part of the operator and is burdensome to the patron; and under present practice, the entire attention of an operator is required for a single patron during the whole treatment which results in high labor cost.

The object of my invention is to overcome the above and other disadvantages and to provide a device for the permanent waving of hair by which the discomfort of the patron, due to heat conditions, is greatly diminished, by which the danger of scalp burns is entirely done away with, by which the time required for the treatment is substantially lessened thereby contributing to the comfort of the patron and the reduction of labor cost, by which the number of steps in preparing the hair for the treatment is reduced and by which the otherwise extremely tiring work of the operator is considerably lessened.

In the making of permanent waves in the hair the common practice is to divide the hair into "blocks" of approximately one square inch and to apply to each block a waving unit comprising a holder for the hair, a waving or curling rod mounted upon the holder and about which the hair is wound and a heater. My invention is directed to an improved holder and insulating or shield-

ing means for protecting the hair and scalp against extreme heat and burns.

By referring to the accompanying drawing my invention will be made clear.

Fig. 1 is a vertical section of one embodiment of my invention on the line 1-1 of Fig. 3, a portion being shown in elevation; Fig. 2 is a side elevation showing the heater superimposed; Fig. 3 is a top plan view on the line 3-3 of Fig. 1; Fig. 4 is a vertical section on the line 4-4 of Fig. 3; Fig. 5 is a detail plan view of the top plate of the holder; Fig. 6 is a detail plan view of the clamping member; Fig. 7 is a detail plan view of the bottom plate member; Fig. 8 is a top plan view, with portions broken away, of the insulating or shield member, and Fig. 9 is a perspective view of the screw for securing the parts of the holder together.

Throughout the figures the same numerals refer to identical parts.

At 1 is shown a portion of the scalp from which the hair 2 extends. Adjacent the scalp is the insulating or shield member 3 comprising asbestos layers 4 and 5, a layer of fibrous material 6 and a top asbestos layer 7. The said layers are provided with circular apertures in registry, thereby providing the opening 8 through which the hair passes. Lying upon the shield 3 and secured thereto by an adhesive is, preferably, an apertured cork disk 9 of less diameter than the shield 3 and into which is pressed the bottom plate 10 of the holder which is provided with an opening 11 which registers with the opening 8 of the shield 3 and the opening in the disk 9. As will be seen, the plate 10 is depressed to form a slideway 12 for the clamping member 13 which comprises a flat strip 14 offset at one end to form a finger hold 15 and provided with a keyhole opening 16. The thickness of the clamping member 13 is substantially the same as the depth of the slideway or recess 12 within which it slides. The top plate 17 of the holder is provided with a circular opening 18 which registers with the openings 8 of the shield and 11 of the bottom plate.

The holder and the shield are secured together by screws 21 which pass through suit-

able openings therefor in the shield, the cork layer or pad and the top and bottom plates 17 and 10, respectively, of the holder. The heads of the screws 21 are preferably seated within the asbestos layer 5 and, in order to provide additional insulation for the heads, small cork disks 22 are positioned against them, the disks 22 being retained by the asbestos layer 4. It has been found in practice that the screws 21 become heated during the use of the device and that the additional insulation provided is desirable.

Within the slideway 12 of the bottom plate 10 is provided an oblong opening 23 for the reception of the oblong tapered head 24 of the screw 25 which passes upwardly through the clamping member 14 within the reduced portion 26 of the keyhole opening 16 and through the opening 27 of the top plate 17 so as to permit the lower interiorly threaded end of the curling or waving rod 28 to thread thereupon.

It will be seen that the screw 25 is locked against rotation by the seating of the head 24 within the opening 23 and that when the rod 28 is threaded onto the screw 25, the plate 10, clamping member 13 and plate 17 are drawn together and held in tight relation until the rod 28 is partly or wholly unthreaded from said screw.

In applying the waving unit to the head of the patron a "block" of hair is passed through the opening 8 of the shield 3, thence through the opening provided therefor in the cork layer 9 and thence through the openings 11 of the bottom plate 10 of the clamping member and 18 of the top plate 17, the clamping member being positioned within the slideway 12 so that the circular portion 16' of the opening 16 is in registry with the openings 11 and 18 whereby hair may be readily passed through the holder. The shield or insulating pad 3 is preferably pressed tightly against the scalp, the hair is drawn tautly through the openings in the shield, cork pad and holder as aforesaid and the clamping member 13 is then pressed inwardly within the slideway 12 thereby causing the hair to be pinched or clamped and securely held in the reduced opening thus formed, the opening 16' therein then being out of registry with the openings 11 and 18, the extent of the opening in the clamping member being reduced to the thickness of the hair passing therethrough. The waving rod 28 is then threaded on the screw 25 until the plate 10, clamping member 13 and plate 17 are tightly drawn together. The hair is then wound spirally about the waving rod 28 as shown in Fig. 1, following which a strip, known in the art as a "strix", of flannel or other suitable material which has been dampened in a suitable steaming solution is tightly wound spirally about the hair. The heater 29 is now superimposed over the waving rod with the hair and flannel strip or

"strix" wound thereabout, a suitable opening being provided in the top of the heater for the passing therethrough of the waving rod 28, the bottom of the heater being seated upon the top of the holder as shown in Fig. 2. The rod 28 is provided with a circumferential notch 30 within which a spring lock 31 engages to hold the heater firmly seated against the holder and provide a substantially airtight joint therewith. The heater is of a well known type and is provided with resistance coils which are heated by electric current supplied thereto by wires 32, 33 which are connected with a lighting circuit or other source of current.

The shield 3 is preferably circular in form and is of a greater diameter than the holder whereby the metal parts of which the latter is comprised are effectually prevented from coming into contact with the hair and scalp and burning them, it being understood that when the heater is operating steam is generated from the strix and the metal parts of the holder become heated. By my improved holder, it will also be observed, escape through the holder to the scalp of the steam and the liquid resulting from condensation is prevented inasmuch as the opening extending from the holder through the shield is sealed by the clamping member in its pinching contact with the hair, as above described.

It will now be seen that the waving rod, holder and shield may be assembled into a unit before applying to the head of the patron and the hair of a "block" may then be readily pulled through openings provided therefor in the shield, cork layer and holder and the clamping member moved into pinching relation with the hair; the waving rod, partly threaded upon the screw 25, is then secured against the top plate of the holder, thereby drawing the shield, cork layer and the holder parts together and firmly securing the hair in the holder as desired; the hair is then wound about the waving rod, the strix applied thereto and the heater positioned.

In practice, the necessary number of waving units are applied to the hair at the same time and they are operated simultaneously. Owing to the protection afforded by my invention against scalp and hair burns, the employment of an attendant for each patron to operate an air cooler is made unnecessary. Furthermore, a single operator is capable of attending to four or more patrons at the same time while hitherto an operator has been required for each patron. The labor cost has accordingly been greatly reduced and with entire safety and less discomfort to the patron.

While I have herein described with particularity a preferred embodiment of my invention, I do not thereby desire or intend to limit myself to the precise details of con-

struction and arrangement of parts as the same may be modified and varied in minor particulars from those shown in the drawings and herein described without departing from the spirit and scope of the invention as defined in the appended claims.

Having thus described my invention, I claim and desire to protect by Letters Patent of the United States:

- 10 1. In a device of the class described, a hair-holder comprising a top plate, a bottom plate, a slideway within said bottom plate, a clamping member within said slideway and slidable therein, said plates and clamping member being provided with openings through which the hair passes, said clamping member being adapted to be moved to intersect the passage formed by said openings in said plates whereby the hair is compressed and securely held.
- 15 2. In a device of the class described, a hair-holder comprising a top plate, a bottom plate, a slideway within said bottom plate, a clamping member slidable within said slideway and means for locking said clamping member within said slideway.
- 20 3. In a device of the class described, the combination of a heat insulating member, a hair-holder secured thereto and comprising a top plate, a bottom plate and a clamping member for securing the hair against withdrawal from the holder, a screw passing through said plates and clamping member and projecting above the top plate and a waving rod threaded upon said screw and about which the hair is adapted to be wound.
- 25 4. In a device of the class described, the combination of a heat insulating member, a hair-holder secured thereto and comprising a top plate, a bottom plate and a clamping member for securing the hair against withdrawal from the holder, a screw passing through said plates and clamping member and projecting above the top plate and a waving rod adapted to be threaded onto said screw to draw said plates and clamping member firmly together and secure said clamping member against movement.

In witness whereof I have hereunto set my hand this 2nd day of April, 1928.

50 HARRY HANOVER.
